CLAIM

The ornamental design for a flexible element, as shown and described.

DESCRIPTION

FIG. 1 is a perspective view of a flexible element holder showing my new design;

FIG. 2 is a top plan view thereof the body portion;

FIG. 3 is a bottom plan view thereof;

FIG. 4 is an elevational view of FIG. 1 with the beaded cord member omitted, the side opposite being a mirror image;

FIG. 5 is a left end elevational view of thereof the body portion;

FIG. 6 is a right end elevational view thereof;

FIG. 7 is a perspective view of the beaded cord member, the side opposite being substantially a mirror image; and

FIG. 8 is a side elevational view of a modified embodiment of the beaded cord member shown in fragment.
